UNITED STATES PATENT OFFICE.

CHARLES SPEARMAN, OF WESTMOUNT, QUEBEC, CANADA.

PULP-HANDLING DEVICE.

Application filed June 25, 1919. Serial No. 306,565.

To all whom it may concern:

Be it known that I, CHARLES SPEARMAN, a subject of the King of Great Britain, residing at Westmount, in the Province of Quebec, Dominion of Canada, have invented certain new and useful Improvements in Pulp-Handling Devices, of which the following is a specification.

This invention relates to an apparatus for the separation and extraction of minerals from their ores and the purification of concentrates.

It has application particularly to an apparatus for use in extracting, separating, and concentrating operations wherein the ore is treated in such fashion that the values and the gangue material are dissimilarly modified, as by supplying the values with a film of material which is immiscible or non-assimilating with the material utilized to modify the gangue, and then producing a stratification in the pulp, the constituent portions of which are thus differentiated, and an agglomeration of the values, and finally a separation of the values from the gangue material.

The principal object of my invention is to provide a form of pulp handling device which may be utilized in a variety of operations for the purpose of enlivening the pulp, agglomerating the desired constituents, producing stratification between the select and the reject constituents, launching the pulp upon a suitable flotation body for surface tension separation, or effecting an actual separation of the stratified constituents.

One of the objects of my invention is to provide an improved pulp handling device wherein the pulp may be treated for the purpose of aerating or enlivening it and wherein the application of the aerating or enlivening fluid contributes to the progressive movement of the pulp over the device, thereby increasing the capacity of the device, and the speed of the separating or launching process.

Another object of my invention comprises the provision of a pulp handling device which produces an enlivening and stratification of differentiated constituents of the pulp both by the filtration of air or other fluid through the pulp, and by a mechanical manipulation of the pulp occasioned by its movement over the device.

Another object of my invention is to provide a pulp handling apparatus wherein the

separation of the agglomerated values is expedited by mechanical means which are rendered effective by the movement of the pulp over the device.

A further object of my invention is to provide a form of pulp handling device which has increased wearing qualities and a term of utility considerably greater than those of devices employed in present practice.

Other and further objects of my invention will be obvious from the following description and claims, or pointed out therein, reference being had to the accompanying drawings forming a part of my application and showing, for the purpose of illustration merely, one of the variety of forms in which the invention may be embodied.

In a copending application, Serial Number 281,017, filed March 6, 1919, I have disclosed and claimed a method for the separation and concentration of ores which is characterized by the fixation of a certain amount of water moisture in the ore, and a subsequent mixing of the ore with water and a non-assimilating agglomerating agent in the nature of an oil, in such fashion that the select value content of the ore is supplied with a film of material which is non-assimilating with a suitable flotation body, preferably water. This process of thus differentiating the values from the reject content of the ore may be accomplished concomitantly with the reduction of the ore to a freely flowing pulp, which operations may be effected in a suitable ball mill or in a mixer, and from such device the pulp is discharged on to a suitable launder and over a distributor.

In the further treatment of the pulp for the purpose of separation and concentration of the values, it is contemplated that the pulp will be subjected to an enlivening and stratifying operation on a suitable device whereon it is treated by the injection of air or other fluid which works it and assists in freeing the values from the other content. My present invention is directed particularly to an apparatus employed at this point in the separation process.

The apparatus constituting my present invention is in the form of a launcher or pulp handling device having a pulp supporting side or surface over which the pulp is passed or flowed. For reasons hereinafter to be pointed out I form this surface in the

shape of a series of steps or stages arranged so that the pulp is discharged from one step or stage on to the next step or stage during its progress over the device. At the upper limits of the several steps or stages means are provided whereby air or other fluid is injected into the pulp, the disposal of the injecting means being such that the fluid streams are directed in a fashion to assist in the progressive movement or flow of the pulp over the apparatus.

In conjunction with this form and arrangement of stepped launching and segregating surface may be utilized a series of gratings or apertured devices over and through which the pulp passes in its movement from one stage to the next. These grating or straining devices are arranged in such fashion as to afford easy passage through them of the more fluid constituents of the pulp, while the more coherent or agglomerated portion, which comprises the desired values, is caught and retained for a period, thus effecting an actual physical separation or stratification of the values from the reject constituents of the pulp.

In the accompanying drawings, Figure 1 is a partly diagrammatic illustration in the nature of a longitudinal sectional elevation through one form of pulp handling device of my improved construction.

Figure 2 is a fragmentary view in the nature of a fragmentary plan or top view of the device.

Figure 3 is a view similar to Figure 1 but illustrating an alternative form of the device.

Figure 4 is a detail in the nature of a fragmentary top view of Figure 3 and illustrating an alternative form of separating member.

Referring to the drawings by means of the reference characters, let it be understood that the numeral 1 designates generally a segregating or launching device which may be in the nature of a hollow structure of sheet metal adjustably supported in operative association with a suitable flotation body, designated by the numeral 2, a distributor designated by the numeral 5, and other apparatus utilized in the separation and concentration process.

The launcher or segregating device 1 may be built up in any suitable fashion on a frame 6, which is effective to sustain the sheet metal wall portions 7 and the pulp supporting side or wall. The hollow structure thus formed is adapted to float on the flotation liquid and is suitable for the reception of fluid, either liquid or gaseous, or both, which may be introduced through pipes or inlets 3. The pulp supporting side, which constitutes the upper wall of the device, is constructed in the form of a series of steps or stages. This portion of the de-

vice may be formed of suitable metal plates disposed to form intermediate zones 8, and stages 9, as illustrated in exaggerated proportion in Figure 1. If desired, the stages may be rendered pervious to fluid by being provided with small apertures 13 which permit the egression of fluid from the interior of the device. Adjacent the upper surface of the several stages 9 the zones 8 are provided with apertures, designated by the numeral 10, which apertures may be formed by spacing the lower margins of the plates forming the zones apart from the upper surfaces of the stages. The essential feature of the arrangement is that the disposal of the apertures 10 be such that the fluid issuing through them from the interior of the device will be directed across the adjacent stage member toward the next lower stage member.

In the operation of the device it is contemplated that pulp of the proper consistency, which has been subjected to the differentiating agents as above described, shall be deposited upon an upper or rear stage of the device from a suitable distributor 5, or similar apparatus. Either from gravity or from the influence of a fluid stream directed from a conduit 11, the pulp is caused to flow over the stage to its lower limit, and then pass on to the next stage. The flow of the pulp across such next stage is assisted by a fluid stream issuing from the apertures 10 at the rear thereof, and the flow of the pulp to the next lower stage thereby expedited. In this manner the progressive flow of the pulp across the pulp supporting side of the device is greatly accelerated, so that the capacity of the device is materially increased. In addition to thus assisting in the progressive movement of the pulp over the device, the moving fluid emitted from the apertures 10 accomplishes the further purpose of aerating the pulp, and of working or enlivening it by the passage through it of such fluid. This has the effect of freeing the discrete particles of the desired values from the other material in the pulp, thereby permitting and assisting the values rising to the surface of the pulp due to the nature of their qualifying films, or to other influences producing stratification. This process of enlivening, freeing, and stratification may be further contributed to by minute fluid streams emitted through the small apertures in the stages. During the progressive movement of the pulp over the supporting surface, a further working or enlivening of the pulp is accomplished by the undulating of the pulp stream in its passage from one stage to the next, thus contributing further to the rapid freeing of the value particles throughout the entire mass of the pulp.

As a result of the effect of this apparatus upon the pulp, the values are freed very

rapidly, and stratified and agglomerated at the surface of the pulp stream, such stratification and agglomeration of the values beginning immediately and increasing during the progress of the pulp over the device. Finally the pulp may be delivered from this device upon a suitable flotation body whereon the values are separated from the other material in the pulp, and from the surface of which the values may be recovered in any effective manner.

In combination with a segregating and launching device of this construction may be employed the further feature illustrated in Figure 2, for the purpose of expediting the stratification and agglomeration of the values in the pulp. This feature of the invention is an arrangement in the nature of a grating or foraminous device, which may be of comb-like form, and which is disposed at the forward or lower limit or margin of each stage, so that it overhangs the next lower stage, as illustrated at 12. The form shown is constructed in the nature of a comb with individually extending tooth or finger members 14, tapering toward their outer extremities, so as to provide interspacing slots of gradually increasing width. The disposal of the upper faces of these members 12 is such as to permit the passage of the pulp over them from their associated stages, and the irregular or serrated margin formed by these members greatly increases the length of the discharge edge over which the pulp has to pass, resulting in a thinning out of the sheet of pulp to a minimum depth at the discharge ends of the stages. As the progressive movement of the pulp carries it over the members 12, its more fluid portion, which will be the portion containing the water and the water soaked and water filmed material, and which will constitute the lower strata in the pulp stream, will flow or fall through the spaces between the members 14; while the more coherent and less fluid portion of the pulp, which will be the values in their agglomerated condition forming the upper stratum of the stream, will be retained or supported by the members 12 for a period of time. This operation upon the pulp, therefore, produces an actual separation of the agglomerated values from the pulp which will assist in the recovery of the values from the pulp. Furthermore, the passage of the more fluid portion of the pulp through the members 12 constitutes a working of the material which contributes to the freeing of the discrete particles of the values remaining in the mass and to their rising and stratification at the surface. The arrangement of the devices 12 is such that their inclination may be varied by adjustment of the slope of the pulp supporting wall.

In Figure 3 is illustrated an alternative construction for the pulp handling device.

In this modification the pulp supporting wall is formed of a series of plates which are laid overlapping one another seriatim to provide the stages, with space left between the juxtaposed plates to provide the apertures 10 through which the fluid may issue into the pulp from the interior of the device. By this construction of the device the number of stages may be greatly increased, and the offset between the stages decreased, so as to provide an apparatus which is adapted to handle a very shallow stream of pulp and move it very rapidly. The apertured separating member 12 may be formed as terminal projections at the margins of the plates as illustrated in Figure 3, their function being as previously described.

As a result both of the individual effect of the several features above described, as well as the conjoined effect thereof when combined in an apparatus, the speed of the separating process is greatly increased, and the percentage of recovered values is considerably augmented. This results in a distinct decrease in the cost of operation, while the construction of the launching device in the manner specified permits the use of sheet metal for the pulp carrying surface, whereby the device is given added durability and an extended term of utility.

Having thus described my invention, what I claim is:

1. In an apparatus for separating ores, a pulp handling device the combination of a pulp supporting wall arranged in the form of a series of stages, an apertured separating device arranged in the path of pulp transmitted on said wall, and a flotation body disposed to receive pulp discharged from said wall.
2. In an apparatus for separating ores, a wet pulp handling device comprising a pulp supporting wall having a plurality of unobstructed stages adapted to support pulp and arranged to discharge pulp from one on to another thereof, apertured separating devices disposed to receive pulp intermediate successive stages with the said parts being arranged to facilitate progressive movement over the stages and prevent its passage therethrough, and a flotation body disposed to receive the pulp discharged therefrom.
3. In an apparatus for separating ores, the combination of a pulp handling device comprising a wall adapted to support and transmit a flowing stream of pulp, an apertured separating device disposed in the path of pulp transmitted on said wall, and a flotation body disposed to receive on its surface pulp from said wall.

4. In an apparatus for separating ores, the combination of a plurality of stages adapted to support pulp and inclined in such manner as to cause the pulp to pro-

gressively move over said stages and arranged to discharge the pulp from one stage on to another, apertured separation devices disposed intermediate adjacent stages, and a flotation body disposed to receive the pulp from one of the lower stages.

5. An apparatus for separating ores comprising in combination, a series of apertured separating devices arranged in stepped relationship, in position to be transversed by a stream of pulp successively, means for injecting fluid into pulp during such movement, and a flotation body disposed to receive pulp from said devices.

15 6. In an apparatus for separating ores, a hollow pulp handling device including a top or pulp supporting wall, said pulp support-

ing wall being in stepped contour and arranged to permit the egression of fluid from within the device into the pulp supported on the top of said supporting wall, and a flotation body disposed to receive pulp from said wall.

7. In an apparatus for separating ores, a pulp handling device including a plurality of pulp supporting stages arranged to facilitate the progressive movement of pulp thereover by gravity, means for directing a fluid to move pulp on said stages, means for adjusting said stages to selective positions to vary the rate of the flow of the pulp, and a flotation body adapted to receive pulp from one of said stages.

CHARLES SPEARMAN.
